UNITED STATES PATENT OFFICE.

WILLIAM ZOERB, OF DEDHAM, MASSACHUSETTS.

DESIGN FOR AN EYEGLASS-CASE.

SPECIFICATION forming part of Design No. 31,070, dated June 27, 1899.

Application filed May 2, 1899. Serial No. 715,369. Term of patent 14 years.

To all whom it may concern:

Be it known that I, WILLIAM ZOERB, a citizen of the United States, residing at Dedham, in the county of Norfolk and State of Massachusetts, have invented and produced a new and original Design for an Eyeglass-Case, of which the following is a specification, reference being had to the accompanying drawing, forming a part thereof.

10 The drawing shows in perspective view an eyeglass-case, illustrating my new design.

The leading feature of my design consists in a lip at the outer edge of each lid of the case, the lip on one lid being located between the middle and one end of the case and the lip on the other lid being located between the middle and the opposite end of the case, so that when said lids are closed together two projecting lips will appear, which break the general curvature of the outer edge of the case.

15 The drawing shows in perspective view an eyeglass-case, illustrating my new design.

The leading feature of my design consists in a lip at the outer edge of each lid of the case, the lip on one lid being located between the middle and one end of the case and the lip on the other lid being located between the middle and the opposite end of the case, so that when said lids are closed together two projecting lips will appear, which break the general curvature of the outer edge of the case.

20 The drawing shows in perspective view an eyeglass-case, illustrating my new design.

The lid *a* has a lip *a'* projecting outwardly from its outer edge, and said lip is located between the middle of the lid and one end of the case. The lid *b* has a lip *b'* projecting outwardly from its outer edge, and said lip is located between the middle of the lid and the opposite end of the case.

When the two lids are closed together, as shown in the drawing, two outwardly-projecting lips will appear, which are separated, so as to break the general curvature of the outer edge of the case.

I claim—

The design for an eyeglass-case herein shown and described.

In testimony whereof I have signed my name to this specification in the presence of two subscribing witnesses.

WILLIAM ZOERB.
